SHOE AND METHOD OF MAKING SAME

Vincent De Liso, Astoria, Long Island, N. Y., assignor to Palter-De Liso Inc., New York, N. Y., a corporation of New York

Application April 21, 1932. Serial No. 606,645

9 Claims. (Cl. 12—142)

The present invention relates to an improved process for the manufacture of shoes and to the improved shoe obtained thereby.

More specifically, my invention relates to an improved process for making shoes which combines certain features of the hand turned process with the advantageous features of the pasting process. My novel process may be applied to the manufacture of either open shank or closed shank

shoes.

The manufacture of shoes by the hand turned process produces, as is well known, a shoe of superior quality due largely to the fact that the sole of the shoe is formed of one piece, so that no

squeaking such as results from relative sliding and friction between the inner and outer soles of double-soled shoes can occur, while at the same time the sole is pliable and flexible and shapes itself comfortably to the foot. The manufacture of shoes by this process, however, has a serious disadvantage in that after the first lasting, when the upper is turned inside out and attached to the sole, it is an extremely difficult and time-consuming operation to remove the shoe from the last, the upper usually having to be moistened to enable it to be stretched over the wooden last. As a result the manufacture of turned sole shoes requires a considerable expenditure of time which correspondingly increases the cost of the shoes. This mode of making shoes has also the disadvantage that in following it, it is difficult properly to shape the arch and heel portion of the shoe, so that while the sole portion of the shoe is in many respects superior to that of welted and pasted shoes produced by known processes, the rear portion of the shoe was frequently not well lasted and lacked the fitting and wearing qualities of shoes produced by other known processes, such as welted shoes or pasted shoes.

With respect to pasted or welted shoes, on the other hand, a more substantial and long wearing shoe is obtained due to the greater thickness and strength of the two soles (outsole and insole) employed in the pasting or welted process. Pasted or welted shoes, however, have the disadvantage that the sole portion is usually too thick, heavy and stiff and in addition there frequently occurred relative sliding movement between the insole and the filler portion between the soles which caused the highly undesirable squeaking.

It is the object of the present invention to provide an improved process for the manufacture of shoes which embodies the advantages of both of the above-mentioned processes while being subject to the disadvantages of neither. The present

invention contemplates a process which may be considered to be a combination of the turned sole and the pasting or welted processes, and is characterized by the production of a shoe which has the light weight and comfort of a turned sole shoe and the sturdiness and fitting qualities of a pasted or welted shoe. It is a further object of the invention to provide an improved process for the manufacture of shoes which reduces to a very considerable extent the time and also the labor required for the making of shoes; and in general to provide a shoe of improved wearing quality and reduced cost.

Described generally, the present invention provides a process for making a novel type of shoe which along its forward or sole portion is turned and sewn but along its shank and heel portions it is pasted. One of the features of my invention resides in the use of a strip of leather as the complete sole of the shoe, which strip is of one piece and is of substantially the thickness of a sole of a turned sole shoe and is channelled along the sole portion thereof (i. e. from the ball region to the toe) and is split along the remainder thereof so as to provide two heel sections one above the other. The lower, or outer, of the heel portions is made to serve as the heel breasting and outer sole, while the upper heel section is designed to be attached to the upper, and acts as the inner sole, the same being notched to permit the upper, which is sewed to the upper surface of the forward or sole portion of the sole, to be folded under the insole section of the heel portion for the purpose of fitting the upper neatly into the sole.

In accordance with the invention, the channelled sole portion of the sole is sewn to the upper of the shoe by a first lasting operation conducted either by hand or by machine, according to any known or approved turned sole process, the upper as usual, being turned inside out. During this operation the two heel sections are temporarily attached to the last but are not permanently attached to the upper. The shoe is then removed from the last and turned right side out and the counters inserted and the second lasting begun, by which the upper heel section is lasted and attached to the upper upon the inside surface of the latter, by the known cementing process, the shank inserted and the heel attached, and the lower section of the heel, i. e. the breasting, then cemented to the outer surface of the upper, to the shank, and to the breast of the heel.

My invention will be described in greater detail in connection with the accompanying drawings

which show by way of example a preferred embodiment of the invention. In said drawings,

Fig. 1 is a perspective view of the sole employed in my improved process, the heel section being split as shown;

Fig. 2 is a view similar to Fig. 1 but shows the sole channelled for stitching along the forward or sole portion thereof and skived at the heel sections;

10 Fig. 3 is a longitudinal section along the line 3—3 of Fig. 2.

Fig. 4 is a view showing the shoe upon a last and turned inside out during the first lasting operation, the forward or sole portion of the sole 15 being sewn to the upper;

Fig. 5 is a view showing the shoe upon a last during the second lasting operation, the shoe having been turned and the upper being drawn in between the two heel sections; and

20 Fig. 6 is a view similar to Fig. 5 but showing the completed shoe, the lower heel section of the sole being broken away.

The sole 10 shown in Fig. 1 may be of the thickness usually employed in turned sole shoes. According to the present invention, the sole is split along the heel section thereof, i. e. from the heel 11 to approximately the ball region 12, thereby producing the upper and lower sections 13 and 14 of approximately equal thickness. If desired, the 30 cut may be so made that the section 13 is thicker than the section 14. The forward or sole portion 10a of the sole 10 is then channelled and a shoulder formed on the edge in known manner, as shown at 15, 15a in Fig. 2, the channelling extending from the toe portion to approximately the ball region of the foot. The lower heel section 14, which is to serve as the heel breasting, is then skived down to the desired thinness, as can be more readily seen in Fig. 3, while if desired the 40 upper heel section 13 may be similarly skived though not to as great a degree; for example, to a thickness of about $\frac{1}{8}$ inch. The upper heel section is notched, as shown at 12a across the channel 15 at approximately its inner end for a purpose to be described hereinafter. It will be understood that these several operations upon the sole may be performed in any desired order, although the sequence indicated is preferred by me.

50 The upper heel section 13, which may be referred to as the insole, may then be supported upon and stiffened by a strip of fiber or board which is glued or otherwise attached to such insole.

55 The shoe is then lasted by the turned sole process, as is well known in the art, by turning the upper 17 and its lining 18 inside out and sewing it and its lining to the upper side of the sole 10 along the channelling, either by hand or by machine as shown in Fig. 4. This operation is well understood in the art and need not be described in detail. The upper is thus stitched either by hand or by machine to the sole portion 10a of the sole 10 from the region of the ball to the toe, along the line of stitching 16, the heel portion of the sole 60 being temporarily fastened to the last by tacks 13a, as shown in Fig. 4.

70 The shoe is then removed from the last. This removal operation is effected with much greater facility and speed than in the case of the regular turned sole shoe because the sole is attached to the upper along only the sole portion thereof. The shoe is then lasted a second time right side out likewise in the manner well known in the turned shoe art, as shown in Fig. 5. During the lasting 75 operation the upper is threaded through the

notches 12a so as to extend between the sections 13 and 14 and is drawn over the insole 13 to which a coating of glue or cement has been applied, the upper being then temporarily attached to the insole, as by means of tacks 19. The back portion 80 of the shoe is now shaped to the heel seat and rear portion of the last in a manner similar to that employed in a welted or pasted shoe. The seat is then nailed and glued and the side of the lasting cemented.

85 The steel shank 20 is now applied, such shank being covered with cloth or other suitable material to enable it to be cemented to the breasting. The shank may be held in place by means of a nail driven into the heel seat. A leather filler 21 90 as shown in Fig. 6 is now applied over the steel shank by glueing the same to the latter, the purpose of such filler being to round out the arch of the shoe and smooth the same. The outer surfaces of the upper which overlie the insole are then roughened to provide a hold for the cement and the cement applied as in the known "compo" process. The heel section 14 is then glued up to the heel seat which is left loose for the heel. Finally the heel is jacked and the breasting 14 100 glued thereto as shown in Fig. 6, after which the shoe is finished in the ordinary manner.

105 My improved process as above described thus produces a shoe having only one sole and therefore possessing the advantages of a turned sole shoe, and at the same time employs the pasted process for the rear half of the shoe which enables the heel region of the shoe and arch to be better shaped and finished. I have thus provided a shoe which is sewn at its forward or sole portion and cemented at its rear or heel portion. I have found by actual comparison that according to my novel process twenty-five pairs of shoes can be lasted and second lasted in the time required for performing the same operations upon eight pairs 115 according to the old turned process. Also only about 40% of the time required for stitching shoes according to the old bench turned process is required to stitch a shoe according to my invention.

120 It will be understood that various changes in the order of operations described above may be resorted to and certain steps may be used without others and that the process may be applied to open or closed shank shoes within the scope of the appended claims without departing from the spirit of the invention.

I claim:

1. In the manufacture of shoes, the steps which comprise splitting the heel portion of a sole to 130 provide a relatively thin lower section and a relatively thick upper section, channelling the forward portion of the sole, stitching such forward portion to a shoe upper, and cementing the two heel sections to such upper.

2. The process as set forth in claim 1, wherein the thick, upper heel section is cemented to the inner surface of the shoe upper while the lower heel section is attached to the outer surface of such upper.

3. The process as set forth in claim 1, wherein the shoe upper is lasted over the upper heel section and is cemented thereto, a shank member is attached to the upper, and the lower heel portion attached to such shank member.

4. The method of manufacturing shoes, which comprises splitting a sole along the heel portion to provide a lower heel section and an upper heel section, channelling the sole portion of said sole so that the inner ends of the channelling terminate 150

- in the region of the ball of the shoe, notching the upper heel section adjacent to the inner ends of the channelling, stitching a shoe upper to said sole portion at said channelling, threading the upper through said notches so that it extends between the upper and lower heel sections, cementing the upper to said upper heel section, applying a shank, and cementing the lower heel section over said shank. 80
- 10 5. The method of manufacturing shoes which comprises splitting a sole along the heel portion to provide an upper and a lower heel section, skiving the lower portion to reduce its thickness, channelling the sole portion of the sole so that the inner ends of the channelling terminate in the region of the ball of the shoe, notching the upper heel section adjacent to the inner ends of the channelling, stitching a shoe upper to said sole portion at said channelling, threading the upper through said notches so that it extends between the upper and lower heel sections, cementing the upper to said upper heel section, shaping the rear of the shoe, forming a heel seat, applying a shank stiffener over the upper, cementing the lower heel section to the upper as far as the heel seat, attaching a heel to the heel seat, and cementing the still free portion of the lower heel section to the breast of a heel. 90
- 15 6. In the manufacture of shoes, the steps which comprise splitting a sole along the rear portion thereof to provide upper and lower sections, stitching an upper to the forward portion of said sole, and cementing such upper between the upper and lower rear sections. 100
- 20 7. A shoe comprising an upper, a heel, and a sole which is split along the heel portion thereof to substantially the ball region, the heel portion being thus divided into a lower section and an upper section, the upper being sewn to the sole portion of such sole and the upper section of said heel portion being cemented to the upper, and the lower of said heel sections providing a breast cover for the heel. 105
- 25 8. A shoe comprising an upper, a heel, a shank, and a sole which is split along the heel portion thereof to approximately the region of the ball, the heel portion being thus divided into a lower section and an upper section, the forward portion of said sole being channelled and sewn to said upper, the upper section of said heel portion being cemented to the inner surface of the upper, and the lower heel section being cemented to the shank of the shoe, and providing a breast cover for the heel. 110
- 30 9. A shoe comprising an upper, a heel, and a sole which is split along the heel portion to approximately the region of the ball, the heel portion being thus divided into a lower section and an upper section, the forward portion of the sole being channelled and sewn to the upper, the inner ends of the channelling terminating approximately in the region of the ball, the upper heel section being notched adjacent to the inner ends of the channelling, the upper extending from the channelling through the notches and between the heel sections, the upper being cemented over the upper heel section, and the lower heel section being cemented along part of its length over the upper and providing a breast cover for the heel. 115
- 35 7. A shoe comprising an upper, a heel, and a sole which is split along the heel portion thereof to substantially the ball region, the heel portion being thus divided into a lower section and an upper section, the upper being sewn to the sole portion of such sole and the upper section of said heel portion being cemented to the upper, and the lower of said heel sections providing a breast cover for the heel. 120
- 40 8. A shoe comprising an upper, a heel, a shank, and a sole which is split along the heel portion thereof to approximately the region of the ball, the heel portion being thus divided into a lower section and an upper section, the forward portion of said sole being channelled and sewn to said upper, the upper section of said heel portion being cemented to the inner surface of the upper, and the lower heel section being cemented to the shank of the shoe, and providing a breast cover for the heel. 125
- 45 9. A shoe comprising an upper, a heel, and a sole which is split along the heel portion to approximately the region of the ball, the heel portion being thus divided into a lower section and an upper section, the forward portion of the sole being channelled and sewn to the upper, the inner ends of the channelling terminating approximately in the region of the ball, the upper heel section being notched adjacent to the inner ends of the channelling, the upper extending from the channelling through the notches and between the heel sections, the upper being cemented over the upper heel section, and the lower heel section being cemented along part of its length over the upper and providing a breast cover for the heel. 130
- 50 10. A shoe comprising an upper, a heel, and a sole which is split along the heel portion thereof to substantially the ball region, the heel portion being thus divided into a lower section and an upper section, the upper being sewn to the sole portion of such sole and the upper section of said heel portion being cemented to the upper, and the lower of said heel sections providing a breast cover for the heel. 135
- 55 11. A shoe comprising an upper, a heel, a shank, and a sole which is split along the heel portion thereof to approximately the region of the ball, the heel portion being thus divided into a lower section and an upper section, the forward portion of said sole being channelled and sewn to said upper, the upper section of said heel portion being cemented to the inner surface of the upper, and the lower heel section being cemented to the shank of the shoe, and providing a breast cover for the heel. 140
- 60 12. A shoe comprising an upper, a heel, and a sole which is split along the heel portion thereof to substantially the ball region, the heel portion being thus divided into a lower section and an upper section, the upper being sewn to the sole portion of such sole and the upper section of said heel portion being cemented to the upper, and the lower of said heel sections providing a breast cover for the heel. 145
- 65 13. A shoe comprising an upper, a heel, a shank, and a sole which is split along the heel portion thereof to approximately the region of the ball, the heel portion being thus divided into a lower section and an upper section, the forward portion of said sole being channelled and sewn to said upper, the upper section of said heel portion being cemented to the inner surface of the upper, and the lower heel section being cemented to the shank of the shoe, and providing a breast cover for the heel. 150
